Todd A. Vaughn(57) **CLAIM**

The ornamental design for a chocolate grater, as shown and described.

DESCRIPTION

FIG. 1 is a perspective view of an example of a chocolate grater in a closed state, in accordance with embodiments; FIG. 2 is a bottom view of the chocolate grater of FIG. 1, in a closed state;

FIG. 3 is a front view of the chocolate grater of FIG. 1, in a closed state;

FIG. 4 is a top side view of the chocolate grater of FIG. 1, in a closed state;

FIG. 5 is a perspective view of the chocolate grater of FIG. 1 in an open state;

FIG. 6 is a side view of the chocolate grater of FIG. 1 in an open state; and,

FIG. 7 is a side sectional view of the chocolate grater of FIG. 1, in a closed state.

The broken lines of the chocolate grater are illustrative and depict environment, and thus, form no part of the claimed design.
